(57) **CLAIM**

I claim the ornamental design for a lens cleaning device, as shown and described.

DESCRIPTION

FIG. 1 is a top perspective view of my design for a lens cleaning device,

FIG. 2 is a top plan view thereof,

FIG. 3 is a left elevation view thereof,

FIG. 4 is a right elevation view thereof

FIG. 5 is a bottom plan view thereof; and,

FIG. 6 is a front elevation view thereof.

The back side is symmetrical to the front side.

1 Claim, 2 Drawing Sheets
